FIG. 1

INVENTOR
Ansel K. Zettler

This technical drawing illustrates a mechanical assembly, possibly a reel or spool mechanism. The drawing is oriented vertically, with the main body of the device on the left and various mechanical components on the right. Key features include a vertical frame on the left with a series of holes labeled 1 through 22. On the right, there are two large circular components, likely reels, labeled 34 and 35. A central vertical shaft or axle is labeled 5. A lever or linkage system is shown on the right, with a connecting rod labeled 45. Other labeled parts include 12, 13, 14, 17, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, and 60.

UNITED STATES PATENT OFFICE.

ARNOLD STUCKI, OF ALLEGHENY, PENNSYLVANIA, ASSIGNOR TO STANDARD STEEL CAR CO., OF PITTSBURG, PENNSYLVANIA, A CORPORATION OF PENNSYLVANIA.

MINING-CAR.

SPECIFICATION forming part of Letters Patent No. 761,264, dated May 31, 1904.

Application filed November 23, 1903. Serial No. 182,341. (No model.)

To all whom it may concern:

Be it known that I, ARNOLD STUCKI, a resident of Allegheny, in the county of Allegheny and State of Pennsylvania, have invented a new and useful Improvement in Mining-Cars; and I do hereby declare the following to be a full, clear, and exact description thereof.

My invention relates to mining-cars constructed of metal; and its object is to improve cars of this type in particulars hereinafter described and claimed.

In the accompanying drawings, Figure 1 is a side view of my improved car. Fig. 2 is an end view of the same. Fig. 3 is a plan view; 15 and Fig. 4 is a transverse section on the line 4 4, Fig. 3.

My car is constructed entirely of metal and has one end of the body open and provided with a swinging door, as is usual with cars of 20 this class. The body comprises a floor plate or plates 1, side plates 2, one stationary end plate 3, and an end door 4. The floor and side plates are connected by means of angle-bars 5, and the latter also serve as the sills, and having the stationary axle 6 secured thereto by 25 means of yokes or other fasteners 7, the wheels 8 being rotatable on the axles, as is common in this class of cars.

The side plates 2 extend substantially vertically slightly above the tops of the wheels and are then flared or inclined outwardly to increase the capacity of the car. The stationary end plate 3 is secured to the side plates by means of internally-arranged angle-bars 30 10, riveted to the side plates and end plate and to the floor-plate by means of a similar angle-bar 11. To facilitate loading, the end plate 3, especially with high cars, is comparatively low, the side plates projecting above 35 the same a considerable distance, as shown in Fig. 4. Triangular gusset-plates 12 are secured to the top edges of the end plate 3 and to the projecting portion of the car sides, being connected to the latter by means of the 40 upwardly-projecting portions of the angle-bars 10 above referred to. The inclined edges of these gusset-plates are flanged outwardly, as at 13, to stiffen the same. The top edge of

the end plate 3 is strengthened by means of a transverse angle-bar 14, riveted thereto, and 50 the top edges of the side plates are also strengthened and finished by means of longitudinal angle-bars 15, riveted thereto.

At the open end of the car the side plates are supported by means of externally-arranged 55 angle-bars 17. Extending across the open end is a transverse angle-bar 18, secured to the top edges of the sides, and to facilitate this connection the outwardly-projecting leg 19 of the angle-bars 15 is bent to a horizontal position, at least at their end portions, as shown at 20, thus giving a horizontal surface for riveting thereto the transverse angle-bar 18. To this transverse angle-bar are secured the hinge-butts 21 for the end door 4. The hinge-straps 60 22 extend practically down to the lower edge of the door, thus strengthening the same, and the door is further stiffened near its lower edge by a transverse angle-bar 23.

The connection between the transverse bar 70 18 and the car sides is strengthened by means of triangular gusset-plates 24, secured to the said transverse bar and car sides.

The free end of the door is locked to the floor by means of an automatic latch, that 75 shown comprising a bent lever 25, pivoted to the door at 26 and having an upwardly-projecting handle 27 and a downwardly-projecting latch 28. The handle 27 is so positioned that its center of gravity cannot come into a 80 vertical line with the center of the pivot 26, so that said lever will act by gravity to keep the latch depressed. The lower end of this latch is beveled, as indicated at 29, as is common with door-latches, so as to slide over the 85 floor-plate and snap into an opening formed in said plate or behind a shoulder formed on said plate. As a consequence when the door is swung to its closed position it will automatically lock without further attention. 90

The floor-plate projects beyond the ends of the car, as at 32, and secured to the lower face thereof underneath the end plate 3 and the door 4 are transverse angle-bars 33, which serve to connect the car sides, especially at 95 the door end, and serve to keep the car in

shape. Abutting against the outer faces of these angle-bars and secured to the lower faces of the projecting portions 32 of the floor-plate are the buffer and coupler castings 34, 5 and also secured to the lower faces of the floor-plate and abutting against the rear side of the angle-bars 33 are the braces 35, which may be either castings or pressed scoop-shaped plates. Buffer-blocks 36 are suitably secured, 10 as by means of bolts, to the buffer-castings 34, these blocks taking the shocks, so that in case of breakage only these small and inexpensive blocks need to be renewed.

The car is provided with brake-blocks 37, 15 one on each side of the car and bearing against the upper portions of the wheels. These brake-blocks are carried on vertical rods 38, guided in brackets 39, secured to the car sides. The lower end of the rod 38 on one side is 20 connected to an arm 40, secured to a rock-shaft 41, extending transversely underneath the car-floor and secured thereto by hangers 42. To the opposite end of this rock-shaft is secured a lever 43, extending out to the end 25 of the car in suitable position to be readily grasped, and the rod 38 on that side of the car is secured to an offset on said lever. Riveted to the car sides is a strap 44, having thereon a bracket 45 for supporting the lever 30 43 to hold the brake-blocks out of contact with the wheels and also provided with a series of ratchet-teeth 46, which are engaged by the lever when the latter is pressed down to apply the brakes.

35 The car described is constructed entirely of metal and principally of standard structural shapes and flat plates. The design is very simple and at the same time a strong car is provided. The locking means for the door is 40 such that it operates automatically when the door is swung to its closed position, and the low stationary end facilitates loading the car by shoveling. It will be obvious, of course, that in place of the angle-bars shown in the 45 drawings other flanged bars—such as channels, T-bars, or the like—may be employed.

What I claim is—

1. A body for mining-cars having one end open and comprising floor and side plates and 50 one stationary end plate, flanged bars connecting said plates, flanged bars secured to the upper edges of the side plates, a flanged bar extending across the open end of the body and secured to the sides, a door hinged to said bar, 55 and means for locking the free end of said door.

2. A body for mining-cars having one end open and comprising floor-plates, one stationary end plate, inclined side plates, means for 60 uniting said plates, flanged bars having one flange riveted to the upper edges of the inclined side plates and having another flange projecting horizontally at its end portions at

least, a transverse bar riveted to the horizontal end flange portion, and a door hinged to 65 said transverse bar.

3. A body for mining-cars having one open end and comprising floor-plates, one stationary end plate, inclined side plates, means for uniting said plates, an angle-bar riveted to the 70 upper edges of the inclined side plates and having one leg at its ends bent to a horizontal position, a transverse flanged bar riveted to said horizontal portions of the side angle-bars, and a door hinged to said transverse bar. 75

4. A body for mining-cars comprising floor-plates, an end plate, side plates projecting above the end plate, means for uniting said plates, and gusset-plates connecting the upper edge of the end plate and the upwardly-projecting portion of the side plates. 80

5. A mining-car comprising floor, side, and one end plate suitably secured together and a door at the opposite end, and a transverse flanged bar riveted to the lower face of the 85 floor-plate below the door.

6. A mining-car comprising floor, side, and one end plate suitably secured together and a door at the opposite end, the floor-plate projecting beyond the end plate and door, transverse flanged bars riveted to the lower face of the floor-plate below the end plate and door, and buffer-castings riveted to the lower face of the projecting portion of the floor-plate and abutting against said transverse angle-bars. 90

7. A mining-car comprising floor, side and end plates suitably secured together, the floor-plate projecting beyond the end plate, a transverse flanged bar secured to the lower face of the floor-plate, buffer-castings secured to the 100 lower face of the projecting portions of the floor-plate and abutting against said transverse bar, and a brace also secured to the lower face of the floor-plate and abutting against said transverse bar. 105

8. A body for mining-cars having one end open and comprising side and floor plates and one stationary end plate, means for uniting said plates, a transverse bar secured to the car sides at the open end of the body, a door hinged to said bar, a stop on the floor-plate, a bent lever pivoted to the door and having a downwardly-projecting latch-piece and provided with a beveled end adapted to slide over the floor-plate and engage said stop, and a weighted arm secured to said latch and projecting upwardly in an inclined direction and so arranged that it cannot pass the center of the lever-pivot. 110

In testimony whereof I, the said ARNOLD STUCKI, have hereunto set my hand. 115

ARNOLD STUCKI.
